UNITED STATES PATENT OFFICE.

BENJAMIN G. BERRIEN, OF BRIDGEPORT, CONNECTICUT.

DRIVE-CHAIN.

No. 905,842.

Specification of Letters Patent.

Patented Jan. 6, 1909.

Application filed December 8, 1905, Serial No. 290,917. Renewed June 23, 1908. Serial No. 440,035.

To all whom it may concern:

Be it known that I, BENJAMIN G. BERRIEN, a citizen of the United States, and a resident of Bridgeport, in the county of 5 Fairfield and State of Connecticut, have invented certain new and useful Improvements in Drive-Chains, of which the following is a specification.

My invention relates to an improvement in 10 detachable rectangular drive chain links used in connection with sprocket-wheels. Heretofore links of this character have been either cast or made from sheet metal. A cast link must necessarily be made bulky in proportion to the size required in order to give the necessary strength, and the sheet metal link being of uniform thickness throughout, the metal cannot be properly distributed so as to support those points where the greatest 20 strain is brought to bear so that, regardless of its size, the link is no stronger than at its weakest part.

My improved link is formed from a bar that has been hot rolled so as to distribute 25 the metal with regard to the proper reinforcement of such parts of the link that is required to withstand the greatest strain. One end of the link, of the character mentioned, has an enlarged portion or head to form the 30 sprocket-bar adapted to contact or roll between the wheel sprockets, and the other end is provided with a smaller portion adapted to be journaled in the head. When the sprocket-link is made of sheet metal, these 35 ends, or a larger portion of them, is made by breaking down the body or central portion of the link and turning the free ends of severed metal in opposite direction to complete these ends. This necessitates increasing the 40 length of the links in order to form these ends, resulting in an increased cost, besides weakening the link by increasing its length.

In my improved link, only so much of its 45 central portion is broken down as is necessary to complete the formation of the sprocket-bar, while the opposite end or journal portion of the link is made solid, thus reducing the length of the link by so much metal as otherwise would be required in 50 forming a portion of such journal from the body of a sheet metal link.

To enable others to understand my invention, reference is had to the accompanying drawings in which:

Figure 1—represents a section of a hot 55 rolled bar from which links are to be severed:

Fig. 2—is a view showing a finished and an unfinished link on the bar: Fig. 3—is a side elevation of a section of a drive-chain formed of my improved links: Fig. 4—is an upper 60 plan view of the chain section shown at Fig. 3.

Its construction is as follows: Rolls, not shown, are used to form the strip or bar shown at Fig. 1, which rolls are so constructed 65 that a greater amount of metal is deposited at the point *a*, one of the weak points of the link. The solid circular end 1 forms the journal portion of the link, presently to be explained, and the lip 2 is a portion of 70 the bearing for this journal. This bar is fed into the proper machine, not shown, to partially break down the central portion of the stock in the link to be formed on the end of the bar, then the bar is advanced to turn 75 this central portion around into a partially closed eye or bearing for the journal 1.

In Fig. 2 a complete link is formed with the lower lip 3 curled around to complete the said bearing, which is broken down from 80 the central portion, as before mentioned leaving the open sprocket space *b* and side bars 4 and 5. At the same time that the lip 3 is carried around in the first link, the lip 3 in the second link is partially broken 85 down, or rather, fully broken down, but not turned, and, at the same time, the completed link is severed from the bar at the point *c*. If the stock is very heavy, the first operation 90 may be to simply mark or outline the point of separation of the lip; the next operation to fully sever the lip on three sides and the third operation to bend the lip around.

It will readily be seen that, if the journal 95 end 1, and the sprocket-bar and bearing for the journal end of the link were both formed from the central or body portion of the stock, the link would have to be correspondingly increased in length, but as only one lip 100 is thus taken out of the body of the link, said link can be proportionally shortened and incidentally strengthened thereby. The weak parts of a link of this character are at the journal-bar end 1, and the point *a* of the sprocket-bar end. As the former is made solid, and the latter is increased in thickness 105 to withstand the necessary strain incidental to breaking down the lip 3, and the working strain on the links when coupled together, as shown at Figs. 3 and 4, it is quite clear that

my improved link possesses advantages over links made out of sheet metal of uniform

thickness throughout, as there is no way such sheet metal links can be reinforced.

Having thus described my invention what I claim as new and desire to secure by Letters Patent is:

A detachable link for drive-chains made of rolled metal comprising a solid circular journal-bar end, a sprocket bar end and bearing for the journal-bar end having one of its lips formed from the central portion

of the link, and reinforced portions *a* to give additional strength to the link, for the purpose set forth.

Signed at Bridgeport in the county of Fairfield and State of Connecticut this 14th 15 day of Nov. A. D. 1905.

BENJAMIN G. BERRIEN.
